(57) **CLAIM**

The ornamental design for a flashlight, as shown and described.

DESCRIPTION

FIG. 1 is a bottom, front, right side perspective view of a flashlight according to the present invention;

FIG. 2 is a top, rear, left side perspective view thereof;

FIG. 3 is a right side elevation view thereof, the left side elevation view being a mirror image;

FIG. 4 is a front elevation view thereof;

FIG. 5 is a bottom plan view thereof;

FIG. 6 is a top plan view thereof;

FIG. 7 is a bottom, front, right side perspective view of a second embodiment of the flashlight of FIG. 1;

FIG. 8 is a top, rear, left side perspective view thereof;

FIG. 9 is a right side elevation view thereof, the left side elevation view being a mirror image;

FIG. 10 is a front elevation view thereof;

FIG. 11 is a bottom plan view thereof; and,

FIG. 12 is a top plan view thereof.

The broken lines are included for the purpose of illustrating an optional clip and form no part of the claimed design.

1 Claim, 4 Drawing Sheets
